CLAIM

The ornamental design for a powered air purifying respirator mount as shown and described herein.

DESCRIPTION

FIG. 1 is a perspective view of the powered air purifying respirator mount of the present invention.

FIG. 2 is a front view of the powered air purifying respirator mount of the present invention.

FIG. 3 is a back view of the powered air purifying respirator mount of the present invention.

FIG. 4 is a top plan view of the powered air purifying respirator mount of the present invention.

FIG. 5 is a bottom plan view of the powered air purifying respirator mount of the present invention.

FIG. 6 is a right-side elevation view of the powered air purifying respirator mount of the present invention; and, FIG. 7 is a left-side elevation view of the powered air purifying respirator mount of the present invention.

The “RPB” logo on the mount forming part of the claimed design is a registered trademark owned by RPB Safety LLC, with a Registration date of Feb. 10, 2009, and Registration No. 3572344.
